UNITED STATES PATENT OFFICE.

OTTO EPPENSTEIN, OF JENA, GERMANY, ASSIGNOR TO THE FIRM OF CARL ZEISS, OF JENA, GERMANY.

COINCIDENCE-TELEMETER.

1,117,820.

Specification of Letters Patent. Patented Nov. 17, 1914.

Application filed February 28, 1913. Serial No. 751,361.

To all whom it may concern:

Be it known that I, OTTO EPPENSTEIN, a citizen of the German Empire, residing at Jena, Germany, have invented a new and useful Coincidence-Telemeter, of which the following is a specification.

The present invention relates to coincidence telemeters, which have two double images of different magnification available for measuring purposes. This result has so far been obtained by arrangements, which allow of one and the same double image being observed alternately under one and the other magnification. In order to change the magnification the observer has to perform a change-over, *e. g.* he has to slide an image-erecting lens-system (a lens-system of reversal) in the ocular from one operative position into the other.

According to the present invention the two double images are presented simultaneously, two oculars being used. When the observer wishes to pass from one magnification to the other, it is only necessary for him to move his eye from one ocular to the other.

Telemeters presenting two double images and having two oculars are known, *e. g.* as stereoscopic ones, in which there is presented to the left and the right eye respectively a double image to be merged into one spatial double image (German patent specification 162471 and patent specification 1,013,849), but also as binocular ones with identical double images (British patent specification 9306/1911) and as coincidence telemeters with inversion of the upper single image in one double image and of the lower single image in the other one (German patent specification 231461). In the last-named case the four (half) single images are obtained by means of a separating prism-system without a real loss of light from the complete images formed by the left-hand and the right-hand objective system. All the means suggested in the above-mentioned publications for the provision of the two double images can serve the purpose of the present invention, when they are combined with means, for giving the two double images different magnifications. Thus, *e. g.*, as in the above-mentioned coincidence telemeter the two double images, which are formed by a separating prism system, may be made use of, when the differ-

ence of magnification is produced by the disparity between the two ocular systems. Where a reduction of the luminosity to one half its value is of no consequence one of the two mixed ray-pencil-systems, which are furnished by the separating prism-system and produce double images, may be allowed to be lost and the other may be split by well-known means into two pencil-systems, each of which then again furnishes a double image. When with the new telemeter the two oculars are so disposed that their axes of emergence are parallel to one another and lie at the interocular distance, the observer can even change the magnification, without having to move his head, by observing, instead of with one of his eyes, with the other one. It will be found convenient in this case to fit a screening device, which may be given two operative positions in such a manner that it liberates one ocular or the other.

In the annexed drawing: Figures 1 and 2 are diagrammatic views in elevation and plan respectively of the optical system of one form of the telemeter according to the invention, the ocular lenses being omitted. Fig. 3 is a section on line 3—3 of Fig. 1, showing the separating prism-system and the two oculars. Fig. 4 is an axial section in the plane of triangulation of a constructional form of a telemeter. Fig. 5 is a section on line 5—5 of Fig. 4.

In the telemeter Figs. 1 to 3, in either double image one single image is erect, the other is inverted. In one double image the erect single image lies above, in the other below the line of coincidence. To the separating prism-system a^1 , a^2 the ray-pencil-systems coming from the objective systems b^1 , b^2 are transmitted by means of two reflecting prisms c^1 and c^2 , which are cemented to a^1 and a^2 , respectively. The rear portion of the cement-layer of the said separating prism-system is replaced by a separating layer a^0 , which is reflecting on both sides. Of the two double images formed in this separating prism-system one is observed through the ocular d^1 , e^1 , the axis of which is inclined upward. In this double image the erect single image lies above the line of coincidence, which is formed by the front edge of the separating layer a^0 . The said single image is derived from the left-hand objective system, and the lower inverted

single image, to which the separating layer a^0 contributes one reflection, comes from the right-hand objective system. The other double image is presented by the ocular d^2 , e^2 , which is intended for horizontal inspection and comprises a reflecting prism f . In this double image the erect single image lies below the line of coincidence and is derived from the left-hand objective system, while the upper single image is a right-hand image and is inverted. The contrast between the two double images, that in one of them the left-hand single image lies uppermost and in the other the right-hand one, ceases, when the reflecting prism f is omitted or just such a prism is introduced into the ocular d^1 , e^1 . In the example shown, corresponding to the shorter focal length of the ocular d^1 , e^1 the double image presented by it is the one having the greater magnification. The displaceable glass wedge g indicates the measuring device.

In the double images presented by the coincidence telemeter, Figs. 4 and 5, both single images are erect. The two oculars have in this example interocular distance and are parallel to each other and the plane of triangulation. The cement-layer of the separating prism system h^1 , h^2 is again replaced as to its upper half by a separating layer h^0 , which is reflecting on both sides. The mixed ray-pencil-system, which emerges from this separating prism-system perpendicularly to the base-line, is received by the right-hand ocular d^2 , e^2 . In the double image presented by this ocular the lower single image is derived from the left-hand objective system, the upper single image from the right-hand one. The mixed ray-pencil-system emerging toward the left and parallel to the base-line from the separating prism-system is received by the left-hand ocular, which is formed as a terrestrial ocular and consists of the following parts: a collective lens i , a reflecting prism h , a lens of reversion l , a field lens d^1 and an eye lens e^1 . In the double image presented by this

ocular the upper single image is derived from the left-hand objective system, the lower single image from the right-hand one. It is assumed, that by the lens of reversion l the double image is reduced, so that the larger double image is presented by the right-hand ocular. A screen m can be displaced parallel to the base-line by means of a pin m^0 in guides n between two stops o^1 and o^2 ; according to its position it closes the right-hand or the left-hand ocular. For deflecting the ray-pencil-system coming from the right-hand objective system, while finding a range, a glass wedge g is again employed, which may be displaced parallel to the base-line by means of a rack g^0 , a pinion p and a milled head p^0 . A scale g^2 , which is connected with the carrier g^1 of the wedge, and the index q belonging to this scale are visible through a window r .

I claim:

1. In a coincidence telemeter two objective systems, a separating prism system, two ocular systems, each of which has a different power and comprises an astronomical ocular, and a measuring device, the said separating prism system being adapted to halve the two images presented by the said objective systems, to compose two double images from these four half images and to present the said two double images simultaneously to the said two ocular systems.

2. In a coincidence telemeter two objective systems, a separating prism-system, two astronomical oculars having different powers and a measuring device, the said separating prism-system being adapted to halve the two images presented by the said objective systems, to compose two double images from these four half images and to present the said two double images simultaneously to the said two oculars.

OTTO EPPENSTEIN.
